UNITED STATES PATENT OFFICE.

HUGH S. NESBITT, OF DETROIT, MICHIGAN.

GINGER-ALE SETTLER.

1,402,528.

Specification of Letters Patent.

Patented Jan. 3, 1922.

Application filed August 26, 1921. Serial No. 495,752.

To all whom it may concern:

Be it known that I, HUGH S. NESBITT, a citizen of the United States, residing at Detroit, county of Wayne, State of Michigan, 5 have invented a certain new and useful Improvement in Ginger-Ale Settlers, and declare the following to be a full, clear, and exact description of the same, such as will enable others skilled in the art to which it 10 pertains to make and use the same, reference being had to the accompanying drawings, which form a part of this specification.

This invention relates to apparatus for 15 settling ginger-ale and similar carbonated fluids, and has for its object an improved device of this character adapted to reduce to the minimum the more or less inevitable foaming of the fluid when it has reached the 20 stage of manufacture where the cooling process is to begin, preparatory to use.

In the drawings:

Figure 1 is a perspective, partly in phantom and partly with a portion of the outer 25 shell broken away to show the disposition of the parts therewithin.

Figure 2 is a sectional elevational view of 30 the device taken through a diameter, its height being purposely abbreviated as shown by the broken lines.

Figure 3 is a plan view of the upper one 35 of the perforated plates or foaming screens, taken along the line 3—3 of Figure 2, and looking in the direction of the arrows there shown.

Figure 4 is a similar view of the lower one 40 of the perforated plates, taken along the line 4—4 of Figure 2, and looking in the direction of the arrows there shown.

45 A indicates an outer shell or drum, preferably composed of two metallic enclosing walls, spaced from one another by filling of non-conducting material, and B represents the inner drum, which is of so much smaller diameter than the outer drum that there is left sufficient space between them for the cooling coils C, and, if desired, an ice packing. The top of both drums is adapted to be closed by the removable cover piece D, 50 provided with a transparent center portion E of the same diametrical size as the smaller one of the drums, so that while the appa-

ratus is in use the degree of foaming of the ginger-ale may be observed through this glass top without removing the cover D as 55 a whole.

The inlet or supply pipe F, controlled by the valve G, enters from without through the walls of the two drums, and then turns right angularly upward. Supported on the collar J, which engages about the upturned pipe, is the lower or finer perforated screen H, which extends completely across the lower portion of the inner drum B. The upper portion of the pipe F is perforated as at L, 65 so that the fluid supplied therethrough may be laterally projected into that portion of the drum B, immediately about the lower screen H. The upper end of the pipe F is closed by the cap M, which is preferably of 70 a "mushroom" form, so as to aid in affecting the lateral projection of the fluid through the holes L and well to the side portions of the drum B before it can rise toward and through the upper and more coarsely perforated plate K, which rests on the top of the cap N. From the space between the bottom of the drum B and the lower plate H, 75 leads the withdrawal pipe M, suitably controlled, as by the faucet P. From the lower portion of the outer drum A leads the sediment vent Q.

In operation, the freshly manufactured carbonated fluid is admitted through the pipe F and emerges with considerable foaming effect through the holes L in the top end of the pipe, and quite soon the foaming portion rises through the larger perforations in the upper plate K, though the passage of even the foaming portion of the fluid 80 therethrough tends to materially reduce that characteristic, and an appreciable quantity of the fluid, now comparatively cleared of foam, falls back through the holes in plate K and around the edges into the space between the plates K and H and thence through the holes in the lower plate H, 85 through which as well there falls at the outset an appreciable quantity of fluid that is free from foam. This is withdrawn through 90 the outlet pipe M. The cooling of the primarily foaming fluid, which at the same time tends to decrease with the drop of temperature, is effected through the medium of the 95 100

coils C, which may be augmented if desired by ice packed thereabout in the space between the drums A and B.

What I claim is:

5. 1. In combination with an outer drum, an inner drum spacedly enclosed thereby, a cooling coil arranged within the outer drum and about the inner drum, a pair of perforated discs spacedly disposed in horizontal planes near the bottom end of said inner drum, a supply pipe adapted to discharge fluid in the space between said perforated discs, and a withdrawal pipe leading from the space beneath the lower one of said perforated discs.
10. 2. In combination with a containing drum, a supply pipe leading from without to a point in the lower portion of said drum, a pair of perforated plates spacedly disposed within said drum above and below the discharge end of said supply pipe, a discharge pipe leading from the space in said drum beneath the lower one of said perforated plates, a cooling coil engaging about said containing drum, and an outer shell spacedly engaging about said cooling coil and said containing drum.
15. 3. The combination, with a pair of drum members spacedly arranged one within the other, of a cooling coil located in the space separating the walls of said drums, a pair of perforated plates spacedly located in substantially parallel planes near the bottom of the inner drum, a supply pipe having its

discharge end located in the space between 35 said perforated plates, and a withdrawal pipe leading from the space in the inner drum beneath the lower one of said perforated plates.

4. In combination with a containing 40 drum, a pair of perforated plates spacedly located therein, a supply pipe having its discharge end located between said perforated plates, means for effecting a lateral deflection of the fluid emerging from the 45 end of said supply pipe, a discharge pipe leading from that portion of said drum beneath the lower one of said perforated plates, and cooling means surrounding said drum.

5. In combination with an inner drum, an outer drum spacedly arranged thereabout in position to contain cooling means in the space separating their walls, a pair of perforated plates spacedly disposed within said 55 inner drum, a supply pipe having its discharge end located between said perforated plates, a withdrawal pipe leading from a position in said inner drum beneath the lower one of said perforated plates, and 60 means appurtenant to each of said pipes for regulating the flow therethrough.

In testimony whereof, I sign this specification in the presence of two witnesses.

HUGH S. NESBITT.
